UNITED STATES PATENT OFFICE.

WILLIAM E. CRANDALL, OF NEW YORK, N. Y.

DESIGN FOR A TEN-PIN.

SPECIFICATION forming part of Design No. 12,016, dated November 9, 1880.

Application filed September 1, 1880. Term of patent 3½ years.

To all whom it may concern:

Be it known that I, WILLIAM E. CRANDALL, of the city, county, and State of New York, and a citizen of the United States, have invented 5 and produced a new and original Design for a Ten-Pin, of which the following is a specification, reference being had to the accompanying drawing, forming part thereof.

The ten-pin heretofore provided consists in 10 a barrel-shaped base, from which rises a cylindrical shaft terminating in a ball. Such a ten-pin, although susceptible of ornamentation, has no inherent divisions separating such different designs as may be placed upon the 15 larger portion of said pin.

The leading feature of my design consists in providing a ten-pin possessing longitudinal parallelogrammic faces, and attaching to or exhibiting on said faces various ornamental, 20 attractive, or instructive devices.

In the drawing the pin is shown in elevation and perspective.

A A' are the parallelogrammic faces or sides

of the larger part of the pin; B, the cylindrical shaft rising therefrom and forming part of the 25 pin; C, the ball or terminal of said shaft and pin.

The design, letter, or other ornamental or instructive device is affixed to or imprinted on or placed upon one or more of the parallelo- 30 grammic faces.

Having thus described my invention, what I claim as new, and desire to secure by Letters Patent, is—

The design for a ten-pin, as herein shown 35 and described, consisting of a ten-pin provided with longitudinal parallelogrammic faces on its lower or larger portion, decorated or ornamented with various attractive and instructive devices, a cylindrical shaft rising therefrom, 40 said shaft terminating in a ball or other symmetrical analogous device.

WM. E. CRANDALL.
